SWIM FIN AND WATER SKI COMBINATION

Bernard N. Rumpel, Deer Park, N. Y.

Application April 18, 1957, Serial No. 45,781

Term of patent 7 years

(Cl. D71—1)

Fig. 1 is a top plan view of a swim fin and water ski combination bodying my new design; and

Fig. 2 is a side elevational view thereof with the fins in a folded position.

I claim:

The ornamental design for a swim fin and water ski combination, substantially as shown.
